CHARLES STRAUSS, OF CINCINNATI, OHIO, ASSIGNOR TO HIMSELF, ADOLPH ULLMAN, AND LOUIS C. STRAUSS, ALL OF CINCINNATI, OHIO.

SPOUT-CAP FOR JARS OR THE LIKE.

1,199,507.

Specification of Letters Patent. Patented Sept. 26, 1916.

Application filed June 5, 1915. Serial No. 32,439.

To all whom it may concern:

Be it known that I, CHARLES STRAUSS, a citizen of the United States of America, and a resident of Cincinnati, in the county 5 of Hamilton and State of Ohio, have invented a certain new and useful Improvement in Spout-Caps for Jars or the like, of which the following is a specification.

This invention relates to spout-caps for 10 use on jars or the like adapted to contain sugar or other similar granular matter for table and other service, and the object of the invention is to provide a cap that has a spout capable of delivering the said sugar 15 or other contents of the jar in measured form so that the user can deliver or discharge the desired quantity of sugar or other contents of the jar to the surface of or into the foods requiring the seasoning. 20 The invention is quite simple in structure, economically made, readily applied to the lid or cap of the vessel or jar and readily cleaned, as well as kept clean from a sanitary point of view. Besides, the device 25 being intended for use in measuring the contents of the vessel, accuracy without waste is assured, and the user knows just what seasoning he is putting in his food which was not possible in the use of the 30 plain form of spout without a regulating device such as has hitherto been provided on the caps or lids of said jars or vessels.

The details of structure will be fully 35 hereinafter described and then more particularly set out in the claim.

In the accompanying sheet of drawings, which serve to illustrate my invention herein,—Figure 1 is a central sectional elevation of the jar or vessel having my improved measuring-cap thereon; Fig. 2, a side-elevation of the jar showing it as it appears in use, with my improved cap or lid thereon and with the measuring-device shown in dotted-lines; Fig. 3, a front-elevation of the lid or cap with my improved measuring-device and spout applied thereto; but omitting the jar; Fig. 4, a plan view of the lid or cap of the jar to which my invention is applied, and Fig. 5, a detail 50 section of the measuring chamber or cup taken on the dotted-line α , α , of Fig. 1.

1 indicates an ordinary glass jar or receptacle adapted to hold sugar or other seasoning material for use in connection 55 with foods, especially in table service. This

jar has a screw-threaded top or rim 2 with a large opening or mouth sufficient to accommodate the improved measuring device therein.

3 indicates a metallic lid or cap that has 60 screw-threaded connection with the screw-threaded top or flange of the jar 1 in the ordinary way common to this type of jars or receptacles.

4 indicates the delivery-spout projecting 65 from the upper outer face of the lid or cap 3, near the edge thereof and having a flap- 70 per-lid 5 that is hinged at 6 to the upper edge of the mouth of the spout, such edge being tapered downwardly toward the edge 75 of the cap. The object of tapering the upper edge of the spout is to facilitate the closing of the hinged lid by gravitating thereon, whereby foreign matter and insects are excluded from within the vessel. 80 The said tapered edge is made to incline downwardly toward the edge of the cap and the lid to hinge at the upper end of said tapered edge so that when the jar is tilted forwardly to discharge its contents, especially such contents as sugar or like granular matter, the said hinged lid serves as a fender to prevent the sugar spraying or scattering forwardly or upwardly away from the direct course intended for it into 85 the food that is to be seasoned.

7 indicates the inner end of the spout that extends vertically and downwardly from the cap into the fore ends of a pair of side-walls 8, 8 of a measuring chamber or cup that has 90 an inclined rear-wall 9, the lower end of which latter wall terminates near the bottom of the inner-extension 7 of the spout. The lower end of the inner-extension of the spout has a removable tight-fitting cap 10, 95 whereby the lower end of the measuring-chamber is closed for use but, at the same time is adapted to be opened for the passage of the cleaning-implement necessary in keeping the chamber in a sanitary condition 100 and affording ready access to the chamber from its said lower end. The upper edges of the side-walls 8, 8 are secured to the inner face of the jar-cap by means of narrow clips or tongue-extensions that extend 105 through slits made in the jar-cap and are upset or turned over, as shown at 11, to secure said measuring chamber or shell in place for use.

The rear-wall 9 is spaced at its upper end 110

2
from the inner face of the cup 3, as best shown in Fig. 1, a notch or opening 12 being provided in each of the side-walls 8, 8, to allow the contents of the vessel to freely 5 enter the measuring chamber or cup when the jar is first tilted and then restored to normal position.

In using the device, it is necessary to first invert the vessel so that its contents shall 10 flow into the upper capped-part of the jar or vessel so that when the jar is returned to normal upright-position a quantity of the contents will remain in the measuring chamber or cup, as shown at α in several levels 15 in Fig. 1, such quantity representing a tea-spoonful or more to suit the standard pre-determined quantity that is to be then discharged on or in the food, as the case may be, when the jar is again tilted forwardly, 20 with the outer end of the spout in direct downward line of discharge, the quantity or amount discharged being that which was left in said measuring-chamber when the vessel was returned to normal upright-position, 25 and no more of the contents can be discharged until the said full tilting operation of the vessel is repeated or duplicated.

In the cross-section shown in Fig. 1, and in dotted-lines in Fig. 3, it will be seen that 30 at the lower end of the spout-extension a lateral or elongated side opening 13 is provided for the outward-passage of the contents of the measuring chamber or cup when the measured-discharge thereof is to be effected 35 through the spout into the food to be seasoned.

It is obvious that other means of fastening the measuring chamber or cup in the jar or vessel cap may be afforded without resorting to that shown in the drawings and referred to in the above description, as the 40

clip or tongue form shown in the drawings might be slightly objectionable on account of the overturned outer ends on the face of the lid or cap being somewhat unsightly and, 45 also, liable to obstruct the use of the cleaning and polishing cloths. It is further obvious that the measuring chamber or cup can be applied within the dome or top of an oil-can or the like to deliver the contents in measured quantities, whereby store and house service can be facilitated with accuracy and without waste and, also, without the use of separate measuring cups or scales that are not always convenient and subject to be mislaid, as well as occupying extra space. 55

I claim:—

A spout-cap for jars or the like comprising a cap or lid, an outwardly-extending spout near the edge of said cap and having 60 its upper edge inclined downwardly toward said edge of the cap, a gravitating-lid hinged to the upper edge of said spout, an inward and downward extension of said spout adapted to be inclosed within the upper part 65 of the jar and having its lower end open, a cap removably-held on said lower open end of the downward spout-extension, and a pair of side-walls extending laterally from said downward spout-extension and having 70 a rear connecting-wall, said downward spout-extension being open at its side in the lower part of the chamber formed by said side and rear walls whereby a measuring chamber or cup is provided for the delivery 75 of the contents of the jar in predetermined quantities.

CHARLES STRAUSS.
